UNITED STATES PATENT OFFICE.

JOSEPH DANIEL MAJORS, OF BRAGG'S, ALABAMA.

AUTOMATIC CAR-COUPING.

SPECIFICATION forming part of Letters Patent No. 351,332, dated October 19, 1886.

Application filed May 25, 1886. Serial No. 203,221. (No model.)

To all whom it may concern:

Be it known that I, JOSEPH DANIEL MAJORS, of Bragg's, in the county of Lowndes and State of Alabama, have invented new and useful Improvements in Automatic Car-Couplings, of which the following is a specification, reference being had to the annexed drawings, forming a part thereof, in which—

Figure 1 is a side elevation, partly in section, of my improved car-coupling. Fig. 2 is a plan view. Fig. 3 is an end elevation. Fig. 4 is an inverted plan view of a portion of a car, showing the arrangement of uncoupling-levers. Fig. 5 is a side elevation of the pivotal support of one of the levers. Figs. 6 and 7 are perspective views of the link.

Similar letters of reference indicate corresponding parts in the different figures of the drawings.

The object of my invention is to provide an automatic car-coupling which may be used in connection with the ordinary coupling-link, thus enabling a car provided with my improved coupling to be connected without inconvenience with cars having the ordinary link and draw-bar.

My invention consists in a draw-bar in which is pivoted a spring-acted catch having a nib adapted to engage the coupling-link, and in the combination therewith of chains and levers for disengaging the catch from the link when desirable.

The draw-bar A is provided with a flaring mouth, a, and a cavity, b, for receiving the coupling-link. It is also provided with a recess, c, in which is pivoted a catch, B, on the pin d, passing transversely through the draw-bar. The catch B is provided with a nib, e, which is beveled on its outer surface and con-caved on its inner surface, and normally rests across the cavity b and extends downward into a small recess, f, formed in the draw-bar below, and communicating with the cavity b. The nib e of the catch B is opposite the pivotal pin d of the catch, and the boss surrounding the pin d bears upon a shoulder, g, at the outer side of the recess c, thus taking part of the strain from the pin d.

To the top of the draw-bar A is secured a curved flat spring, C, by means of the tap-bolt h. The spring C extends over the top of

the catch B, and presses upon the upper surface of the catch near its free end, the spring being arranged to constantly press the catch downward into position for engagement with the coupling-link of the adjacent car. The draw-bar A is supported in the usual way by a strap, D, on the car-frame, which permits it to be moved laterally and vertically. The inner end of the draw-bar A is provided with a rounded shank, E, which is received in the hanger F, and is provided with a nut, i, behind the hanger. A spiral buffer-spring, G, is placed around the shank E, between the hanger and the end of the larger part of the draw-bar.

The free end of the catch B is provided with an eye, j, for receiving the chain k, which extends over a sheave, l, supported by the car-frame, thence backward under the car, where it is connected with two chains, m m', attached to hand-levers n n' under the car. The lever n' is pivoted in the side timber, o, of the car-frame, and extends across the frame through a notch, p, in the lower edge of the timber o'. The end of the lever n' projects beyond the timber o' within easy reach. The lever n is pivoted in a strap, q, secured to the under surface of the timber o', and bridging the notch p. The lever n extends through a notch, p', in the under surface of the timber o, and is confined in the notch by a strap, q', extending across the notch and secured to the under surface of the timber o. At the inner end of each notch p p' is formed a recess, r. The lifting of the catch B from the link contained by the draw-bar is effected by drawing back one or the other of the levers n n', and the catch B may be retained in a raised position by lifting the lever by which it is raised into the notch r.

To the end of the car is pivoted a lever, n³, which is connected with the chain k by the chain m³. By raising the lever n³ the catch B will be raised and disengaged from the link contained by the draw-bar.

The coupling of adjacent cars is effected automatically by the engagement of the link of one car with the beveled nib e of the catch of the adjacent car, the pressure of the link upon the catch causing the catch to rise and pass over the end of the link.

To permit of employing the draw-bar A in

connection with the ordinary link, in case of injury to the catch B, the draw-bar is provided with a pin-hole, *s*, for receiving the ordinary coupling-pin. To adapt the coupling to cars of different heights, straight or bent links will be employed.

Having thus described my invention, what I claim as new, and desire to secure by Letters Patent, is—

- 10 1. In an automatic car-coupling, the combination, with the draw-bar A, provided with a recess, *c*, concave shoulder *g*, and link-receiving cavity *b*, of a catch, B, pivoted in the recess *c*, and provided with a beveled nib, *e*, concaved on its inner surface, and the spring C, secured to the draw-bar and arranged to press the catch B into engagement with the coupling-link, substantially as herein shown and described.
- 15 2. In an automatic car-coupling, the combination, with the spring-acted catch B, provided with the eye *j*, of the chain *k*, sheave *l*, chains *m m'*, and levers *n n'*, oppositely ar-

ranged with respect to each other, substantially as herein shown and described.

3. In an automatic car-coupling, the combination, with the spring-acted catch B, provided with the eye *j*, of the chain *k*, sheave *l*, chains *m m'*, levers *n n'*, oppositely arranged with respect to each other, the straps *q q'*, and 30 timbers *o o'*, provided with notches *p p'* and recesses *r*, substantially as herein shown and described.

4. In an automatic car-coupling, the combination, with the draw-bar A, provided with 35 the link-receiving cavity *b*, pin-hole *s*, and recesses *c f*, of the catch B, pivoted in the recess *c*, and provided with the beveled and concaved nib *e*, and the spring C, secured to the top of the draw-bar and bearing on the catch B, substantially as herein shown and described.

JOSEPH D. MAJORS.
